His Attorney.

UNITED STATES PATENT OFFICE

OLIVER W. GREENE, OF PITTSFIELD, MASSACHUSETTS, ASSIGNOR TO GENERAL ELECTRIC COMPANY, A CORPORATION OF NEW YORK

CENTRIFUGE BUCKET

Application filed September 13, 1929. Serial No. 392,415.

The present invention relates to centrifuge buckets such as are used in the manufacture of rayon, for example. Such buckets are mounted on a vertical shaft, usually the shaft 5 of an electric motor, and are required to rotate at a high speed. Buckets of the constructions now in use are capable of operating at speeds of the order of 7,500 R. P. M., and in some instances at speeds as high as 10 10,000 R. P. M. However, with the demand for finer twisted rayon, there are required centrifuge buckets capable of operating at speeds substantially greater than those heretofore used, and the primary object of my 15 invention is to provide an improved centrifuge bucket which is capable of operating at such higher speeds.

A further object of my invention is to provide an improved construction and arrangement for holding the cover of a centrifuge bucket in position.

For a consideration of what I believe to be novel and my invention, attention is directed to the following specification and the 20 25 claims appended thereto:

In the drawings, Fig. 1 is a side elevation of a centrifuge bucket embodying my invention, and Fig. 2 is a transverse sectional view thereof.

According to my invention I form the lower portion 1 of the bucket from a suitable molding compound, such as a resinous compound which is converted by heat or by heat and pressure into an infusible insoluble state, 30 and a suitable filling substance, such as wood pulp, but instead of forming the upper portion of this same material, I construct such upper portion 2 of a substantially stronger material, as hereinafter described, and make 35 the upper portion relatively thin. In addition to the foregoing, I add additional material to the lower portion of the bucket as is indicated at 3 for the purpose of making the moment of inertia about the vertical axis 40 greater than the moment of inertia about the horizontal axis through the center of gravity of the bucket. In Fig. 2, the horizontal axis through the center of gravity of the bucket is indicated at C. By making the upper portion 45 of the bucket of relatively thin strong

material, and by adding material at the lower portion of the bucket, I am enabled to so distribute the material in the bucket as to make the moment of inertia about the vertical axis sufficiently greater than the moment of inertia about the horizontal axis through the center of gravity of the bucket that the bucket is stable at high speeds, even though it is slightly out of balance due either to its inherent structure or to the material in it. At 55 the same time, the upper portion or rim of the bucket is strong enough to withstand the high centrifugal stresses to which it is subjected.

In carrying out my invention, I form the upper portion of the bucket from twisted spinnable fibers, such as hard twisted cotton or linen cord united by a resinous compound which is converted by heat or by heat and pressure into an infusible, insoluble state. 60 The cord may be wound to the desired shape on a form prior to molding, and then placed in the mold in which the bucket is to be made. As a resinous compound I use preferably a 65 phenolic condensation product.

The driving plate for the bucket is indicated at 4, the seat for the bucket being indicated at 5, and the driving stem at 6. 7 is the driving shaft which may be, for example, the shaft of an electric motor. It has a slight 70 taper as does also the opening through stem 6 with which it forms a driving connection. The bucket is provided with a bushing 8 which may be made of bronze or other suitable material, and in which stem 6 fits. To 75 permit of the ready removal of bushing 8, I provide opposed recesses 9 in the lower end of the bucket through which the hooks of a suitable bushing puller may be inserted to engage in a groove 10 in the bushing. 80 85 90 indicates the openings in the bucket through which liquid is discharged.

If found desirable, I may provide reinforcing means for the peripheral portion of enlargement 3, and in the drawings (Fig. 2) 95 such a reinforcing means is indicated at 12, it being indicated in the form of cord material surrounding and forming a part of such peripheral portion.

The cover of the bucket is indicated at 13, 100

and for holding it in place against its seat 14 I provide a relatively soft rubber ring 15 which fits in a groove 16 formed in the bucket wall just above the cover. With this arrangement, when the bucket is rotating, the rubber ring expands tightly into the groove due to centrifugal force, and holds the cover tightly in place. For high speed work, the bucket must be nicely balanced, and the higher the 10 speed the better must be the balance. A slight amount of unbalance at the rim especially has an adverse effect on the running. The use of a rubber ring for holding the cover in place has the advantage that it is fairly 15 light in weight, uniform in structure, and expands evenly all around under the action of centrifugal force, so that it does not affect adversely the balance at high speed.

I have described what I now regard as the 20 preferred form of my invention. It is to be understood, however, that this is only one structural example of my invention and that it may be carried out by other means, such as come within the scope of the appended 25 claims.

What I claim as new and desire to secure by Letters Patent of the United States, is:

1. A molded centrifuge bucket having its 30 upper portion formed of circumferentially extending cord of twisted spinnable fibers united by a resinous compound.

2. A molded centrifuge bucket having its 35 lower portion formed from a molded substance comprising a resinous compound and a filling substance, and its upper portion formed of hard twisted cord wound circumferentially.

3. A molded centrifuge bucket having its 40 lower portion formed from a molded substance comprising a resinous compound and a filling substance and its upper portion formed from twisted spinnable fibers united by a resinous compound, the material in said bucket being so distributed that the moment 45 of inertia about the vertical axis is greater than the moment of inertia about the horizontal axis through the center of gravity of the bucket.

4. A molded centrifuge bucket having its 50 lower portion formed from a molded substance comprising a resinous compound and a filling substance and its upper portion formed from circumferentially extending twisted spinnable fibers united by a resinous 55 compound, the material in said bucket being so distributed that the moment of inertia about the vertical axis is greater than the moment of inertia about the horizontal axis through the center of gravity of the bucket.

60 5. A molded centrifuge bucket at least a portion of which comprises circumferentially extending cord of twisted fibers united by a resinous compound.

65 6. A molded centrifuge bucket the upper portion of which comprises circumferentially

extending cord of twisted fibers united by a resinous compound.

In witness whereof, I have hereunto set my hand this 11th day of September, 1929.

OLIVER W. GREENE.
